GAS BURNER

Sven W. E. Andersson, Evansville, Ind., assignor
to Servel, Inc., New York, N. Y., a corporation
of Delaware

Application June 18, 1937, Serial No. 148,841

4 Claims. (Cl. 158—117.1)

My invention relates to gas burners, and has as one object the provision of a gas burner having an improved valve structure and safety cut-off mechanism to effectively shut off the flow of gas when the burner flame is extinguished.

Another object of my invention is to provide an improved safety cut-off mechanism which is compactly arranged in a gas burner and can be easily manipulated to instigate operation of the burner.

A further object of my invention is to provide an improved air shutter control for dependably controlling the quantity of primary air admitted into a burner to provide a combustible gas mixture.

The above and other objects and advantages of my invention will be better understood as the following description proceeds, and the features of novelty which characterize my invention are pointed out with particularity in the claims annexed to and forming a part of this specification.

In the drawings, Fig. 1 is a vertical sectional view of a gas burner embodying my invention; Fig. 2 is a sectional view taken on line 2—2 of Fig. 1; Fig. 3 is a vertical sectional view taken on lines 3—3 of Figs. 1 and 2 with the burner tube omitted to illustrate parts of the safety cut-off mechanism more clearly; Fig. 4 is a sectional view taken on line 4—4 of Fig. 3; and Fig. 5 is a fragmentary sectional view of the top part of the burner taken on line 5—5 of Fig. 4.

Referring to Figs. 1 to 3 inclusive, the improved gas burner embodying the invention includes a body member 10 having a hollow boss 11 which may be secured to a suitable support by a screw 12. The body member 10 is provided with a second boss 13 having a threaded opening 14 which is adapted to be connected to a conduit of a gas supply line. The opening 14 communicates with a chamber 15 which in turn communicates with a passage 16 through an opening 17 formed in a valve seat 18. The valve seat 18 is threadedly secured at its upper end within body member 10 and is provided with a cross passage 16' which is in open communication with passage 16. The flow of gas through the opening 17 in valve seat 18 is controlled by a valve 19 which forms part of the safety cut-off mechanism hereinafter to be described.

The passage 16 is in line with the threaded opening 14 and the right hand end thereof is permanently sealed with a plug 20. The opposite end of passage 16 communicates with a chamber 21 from which a passage 22 extends to the bottom of body member 10. The passage 22 is

threaded to receive an adjustment screw 23 and a removable cap screw 24 to seal the lower end of the passage. By removing cap screw 24 the adjustment screw 23 may be set to any desired position opposite the end of passage 16 to control the maximum flow of gas to the burner and hence the maximum size of the burner flame.

The adjustment screw 23 is formed with a passage having a restriction 25 intermediate its ends, whereby the gas pressure in chamber 21 can be measured at any time by removing cap screw 24 and securing a manometer to the lower end of passage 22. When the gas in chamber 21 is not at the desired pressure, the adjustment screw 23 may be moved to increase or decrease the flow of gas from passage 16 into chamber 21.

The chamber 21 is L-shaped, as shown in Fig. 3, and is open at the top of the body member 10. A member 26 having a passage 27 which converges and terminates in a discharge orifice 20 27' is secured to body member 10 at the opening of chamber 21. Within passage 27 is fitted a plug 28 having grooves 29 about the edge thereof. The grooves 29 are at an angle to the direction of flow of gas in passage 27 to impart a whirling motion to the gas.

To the top of body member 10 and about the member 26 is secured a housing 30 having a reduced narrow portion or partition 31 intermediate its ends to form a lower chamber 32. The chamber 32 is provided with air inlet ports 33 and constitutes a mixing chamber in which air and gas are thoroughly mixed to provide a combustible gas mixture.

To the reduced portion 31 of housing 30 is secured the lower end of a burner tube 34 at the upper end of which is provided a cap 35 having a plurality of openings 36. The gas mixture formed in chamber 32 flows upward through burner tube 34 and is discharged at the openings 36 at which region the burner flame is produced and maintained.

A tube 37 concentrically disposed about burner tube 34 is secured by screws 38 to the body member 10. With this arrangement, primary air admitted into mixing chamber 32 through air inlet ports 33 is drawn downward through the upper open end of tube 37. With the upper end of tube 37 closely adjacent to the openings 36 in cap 35, the direction of flow of air drawn downward in tube 37 is reversed considerably due to the fact that the flow of air about the burner flame is upward, as indicated by the arrows in Fig. 1. With such change in direction of the flow of air, particles of dust and lint in the air tend to

move upward about the burner flame and are separated from air which is drawn downward within tube 37. The tube 37, which may be referred to as a dust prevention tube since it insures delivery of clean primary air into the mixing chamber 32, is described more fully in Forberg Patent No. 2,069,062.

About the housing 30 is arranged a vertically movable sleeve 39 having an outward extending flange 40 at its lower end. The flange 40 is bifurcated, as shown most clearly in Fig. 2, to receive a reduced portion of an adjustment screw 41. The adjustment screw 41 extends downward and is in threaded engagement with a passage 42 in body member 10. By turning adjustment screw 41 from the lower open end of passage 32, the sleeve member 39 may be moved vertically to any desired position to control the quantity of primary air admitted into mixing chamber 32 through the air inlet ports 33.

In order to shut off flow of gas to the burner, if for any reason the burner flame is extinguished, I provide a safety cut-off mechanism including the valve 19 in chamber 15. The valve 19 is cup-shaped and formed of thin metal so that the upper open end will be flexible. The valve 19 fits within a rigid cup 43 having a flange 44 about its upper edge. A coil spring 45, which is disposed about cup 43 and bears against the flange 44 and a removable cap screw 46, is provided to urge valve 19 to its closed position on valve seat 18. While the closed end of valve 19 fits snugly within the rigid cup 43, the upper flexible edge of the valve is spaced from the inner wall of cup 43, so that the valve will snugly fit on the lower conical portion of valve seat 18 when the valve is urged upward to its closed position.

The closed end of valve 19 is provided with a small depression to receive the lower end of a pin 47 which extends upward through the opening 17 of valve seat 18 and a sleeve 48 which is formed integrally with the valve seat. A hollow guide 49 closed at its upper end fits over and is vertically movable along sleeve 48. The upper end of pin 47 bears against the closed end of guide 49 whereby downward movement of the guide moves valve 19 to its open position against the action of coil spring 45.

Downward movement is imparted to guide 49 by pulling a button 50 which is movable in a recess 51 at the bottom of body member 10, as shown in Fig. 1. The button 50 is arranged to move a rod 52 which extends upward through a passage in body member 10 and is looped at its upper end. The looped upper end of rod 52 fits into an opening in a strip of metal 53 which is curved and extends vertically within tube 37. The strip 53 is secured at its lower flanged end to guide 49 whereby valve 19 is moved to its open position when rod 52 is moved downward by pulling button 50 out of recess 51.

To maintain valve 19 in its open position during operation of the burner, the upper end of strip 53 is provided with an inward extending flange 57 having an elongated curved opening 58, as shown most clearly in Fig. 4. Within the upper part of tube 37 and projecting slightly above the open end thereof is disposed a bimetallic strip 59 in the form of a split ring. The diameter of the bimetallic strip 59, which will be referred to as a thermal element, is slightly smaller than the inner diameter of tube 37 and the free ends thereof are in the region of the upper flange 57 of strip 53. The thermal element 59 is positioned adjacent a plurality of

openings 66 formed in tube 37 and is secured to the latter at a region intermediate its free ends, as indicated at 60 in Fig. 4. Adjacent its free ends the thermal element 59 is slotted at 61 and 62, as shown most clearly in Fig. 5, to provide downward extending ears 63 and 64 which extend through the curved elongated opening 58 in flange 57. One of the ears 64 is notched at its lower end to provide a shoulder or stop 65 to maintain valve 19 in its open position during normal operation of the burner, as will now be described.

The operation of the burner and safety cut-off mechanism is substantially as follows: To start the burner the button 50 is pulled out of recess 51. This moves rod 52 downward and imparts downward movement to guide 49 and pin 47, whereby valve 19 is moved to its open position against the action of coil spring 45. This permits gas to flow from chamber 15 through the opening 17 in valve seat 18, passage 16, chamber 21, passage 27, and discharge orifice 27' to the mixing chamber 32. In chamber 32 gas is mixed with primary air which is admitted through air inlet ports 33 and controlled by the sleeve or air shutter 39. The gas mixture flows upward through burner tube 34 and openings 36 at which region the mixture is ignited to provide the burner flame.

When button 50 is moved out of recess 51 the strip 53 is moved downward from the position shown in Fig. 3 to the position shown in Fig. 5 with the flange 57 below the shoulder or stop 65 formed on ear 64 of thermal element 59. The thermal element 59 is heated by the burner flame and expands or flexes outward to move the ears 63 and 64 away from each other. When thermal element 59 is heated sufficiently and the ears 63 and 64 have moved apart a definite distance, the shoulder 65 on ear 64 will extend or project past an edge of the opening 58 in flange 57. When this occurs button 50 may be released to move flange 57 against the stop 65, so that upward movement of strip 53 by coil spring 45 will be prevented and valve 19 will remain in its open position.

If for any reason the burner flame is extinguished the thermal element 59 will no longer be heated, whereby the ears 63 and 64 will move toward each other with cooling of the thermal element. With sufficient cooling of the thermal element, the stop 65 will slip off the edge of the elongated opening 58 and no longer be effective to prevent upward movement of strip 53. With stop 65 out of the path of movement of flange 57 the coil spring 45 will become effective to move pin 47 upward and also move valve 19 to its closed position, thereby completely shutting off the flow of gas to the burner.

The thermal element 59 is preferably arranged to fit snugly within tube 37 when it is heated and flexed outward during normal operation of the burner. When the tube 37 is provided with openings 66 at the region of the thermal element 59, these openings will be fully closed when the thermal element is heated and bearing against the inside of tube 37. This prevents dust from entering tube 37 through the opening 66, and all of the primary air admitted into mixing chamber 32 is drawn downward from the upper open end of tube 37. When the burner flame is extinguished and the thermal element 59 moves away from the inside of tube 37, the openings 66 permit flow of air into the tube to hasten the cool-

ing of the thermal element and decrease the time for closing valve 19.

The cup-shaped valve 19 formed of thin metal differs considerably from the usual ball type 5 valve that is generally used to control the flow of gas in gas burners. The flexible edge of the valve insures a snug fit of the valve on the conical or tapered valve seat 18 even when the valve and valve seat are at an angle and not in true 10 alignment. In addition to insuring a tight fit at all times to shut off the flow of gas, the flexibility of the cup-shaped valve 19 possesses the further distinct advantage that it is self-adjusting and does not require the use of materials, such 15 as leather or rubber composition, which are not suitable for use at high temperatures.

When valve 19 is in its open position there may be the possibility of gas leaking between pin 47 and sleeve 48 and between sleeve 48 and guide 20 49. These parts are preferably made with a close sliding fit to reduce the likelihood of gas leakage. The pin 47, sleeve 48, and guide 49 may be coated with a suitable lubricant, such as graphite, for example, to seal these parts and 25 prevent any leakage of gas. Even if a small amount of gas should leak past these parts, such gas passes into the lower part of tube 37 and is drawn into the mixing chamber 32 with primary air. With a burner construction of this type, 30 therefore, it is not necessary to employ any packing about a valve stem or other part which extends through an opening in a body member or valve casing and is arranged to control a valve. The gas burner I have provided is extremely reliable 35 in operation and is particularly adapted for use where a burner is required that must operate with a minimum amount of attention. One such use, for example, is that of heating absorption refrigeration apparatus.

The air shutter control has been so arranged 40 that it will be dependable and will always maintain the air shutter 39 in the position to which it is adjusted. This is effected by providing the adjustment screw 41 which is connected directly 45 to the air shutter and is also in threaded engagement with the passage 42 in body member 10. Movement can only be imparted to air shutter 39 by turning adjustment screw 41, the latter preferably being arranged within the body member 50 10 so that accidental movement of the air shutter cannot be effected.

By making the operating button 50, gas pressure adjustment screw 23, and air shutter adjustment screw 41 accessible from the bottom of the 55 body member 10, the burner may be effectively employed in a horizontal position in a confined space and easily adjusted for the best operation in any particular case.

Although I have shown and described a particular embodiment of my invention, it will be apparent that modifications and changes may be made without departing from the spirit and scope 60 of the invention, as pointed out in the following claims.

What is claimed is:

1. In a gas burner, a burner tube, a second tube disposed about said burner tube and having a plurality of openings, a valve for controlling flow of gas, resilient means for closing said valve, 5 mechanism for manually opening said valve against the action of said resilient means, a ring-shaped thermal element located within said second tube adjacent the openings therein and responsive to the temperature of the burner flame, 10 said thermal element being associated with said mechanism and operative to keep said valve open after operation of the burner is instigated and said thermal element is heated, said thermal element permitting said resilient means to close said 15 valve when it is cooled and the burner flame is extinguished, said thermal element being arranged to close the openings in said second tube during operation of the burner and to permit flow of air through the openings when the burner 20 flame is extinguished.

2. In a gas burner, a burner tube, a second tube disposed about said burner tube and forming the sole inlet for primary air, a valve for controlling flow of gas to said burner tube, resilient means 25 for urging said valve to its closed position, an elongated member disposed within said second tube and operatively associated with said valve, a thermal element in the form of a split ring disposed within said second tube and secured thereto 30 at a region intermediate its free ends, said thermal element having ears at its free ends, said member having an opening to receive said ears, a part operatively connected to said member for manually moving said member and opening said 35 valve against the action of said resilient means, one of said ears having a catch adapted to overhang an edge of the opening in said elongated member when said valve is opened and said thermal element is heated to maintain said member 40 in position to keep said valve open, and said catch moving off the edge of the opening when the burner flame is extinguished and said thermal element is cooled to permit said resilient means to close said valve.

3. A gas burner comprising a valve housing, a burner tube extending from said housing, a dust prevention tube surrounding said burner tube and forming the sole inlet for primary air, said dust prevention tube being provided with an opening 50 adjacent the flame tip of said burner tube, a thermostatic element in said dust prevention tube adjacent the flame tip of said burner tube, said thermostatic element being arranged to block said opening when expanded upon heating, and uncover said opening upon contraction, a cutoff valve in said housing, and a member within said dust tube operatively connecting said thermostatic element and valve.

4. A gas burner as set forth in claim 3 in which 55 said thermostatic element is in the form of a split ring secured intermediate its ends to said dust prevention tube.

SVEN W. E. ANDERSSON.
